HARNESS FRAME CONNECTOR

Paul C. Consoletti, Milford, Mass., assignor to
 Draper Corporation, Hopedale, Mass., a corpora-
 tion of Maine

Application January 11, 1952, Serial No. 265,951

5 Claims. (Cl. 139—88)

1

This invention pertains to an improved connecting means forming a part of loom harness frames and by which said frames are attached to the harness cords or similar means by which the frames are actuated.

It is a general object of the invention to devise a simple connecting means of the type described which shall be adjustable within limits, easily attachable to or detached from its cord or the like, and which shall further have as a co-operating part thereof a locking means adapted to serve the multiple function of maintaining the adjusted position of the connecting means and also, of preventing unintended detachment of the cords or the like.

Other objects and the manner in which the invention is to be put into practice will be apparent from the following more detailed description.

Looms for weaving are provided with two or more harness frames carrying numerous heddles through which are threaded warp threads. These frames are reciprocated in a manner known to those conversant with the art through connections in the form of cords, straps or the like which are attached by various forms of connecting means to the top and bottom rails of the frames. A simple form of hook is frequently utilized, the same being threaded into the wood or other frame material. It is desirable that these hooks or eye screws be so disposed as to be threaded into or from the frame a few turns for adjustment purposes and that they be locked in a particular adjusted position. To that end, according to the prior art, the hook shanks have been flattened for a short distance, and a detent having a fork at one end for engaging the flattened shank screwed to the frame. The detent has no other effect than that of preventing turning of the threaded connector and, in the event an adjustment is to be made, considerable time and effort is involved in removing the holding screw for the detent, effecting the adjustment, and then returning the detent to position and inserting and tightening the screw.

According to the invention, a simple eye screw or hook with a threaded shank or the like, is locked in position by a small, spring strip fixed at one end adjacent the eye or hook and having at its other end some sort of slot which is positioned to embrace the hooked portion of the connection in a manner to prevent its turning and also, so as to prevent unintended detachment of the cord or other harness member by which the frame is actuated. To release a cord for detachment or to free a connector for adjustment, it is only neces-

2

sary to press the spring locking member toward the frame rail. After release, it immediately springs back to its normal locking position.

The invention will be described in greater detail by reference to the accompanying figures of drawing wherein practical forms of the invention have been shown. In the drawings:

Fig. 1 is an elevational view of a harness frame to which the invention has been applied.

Fig. 2 is a perspective view showing one form which the invention may take.

Figs. 3 and 4 are views similar to Fig. 2, but showing other forms of the invention.

Now referring to Fig. 1, a harness is normally comprised of top and bottom rails 10 and 11 tied together at their ends to struts 12 and 13 to form a rigid rectangular structure. The rails are frequently of wood and the struts of metal, but other materials are employed and for the purposes of this invention the materials are not of importance. A plurality of heddles 14 are threaded onto and carried by heddle bars 15 and 16 supported at their ends in the struts 12 and 13, and intermediate their ends by hangers 17 at appropriately spaced intervals. Other heddle supporting means are commonly used and that herein shown is merely given by way of illustration.

At a point adjacent each end of both the top and bottom rails provision is made for connecting the frame unit to harness cords, straps or the like which run to top or other motions and to harness cam and treadle means all in a manner well known and a description of which need not be given here. These cords are designated at 18 and terminate in a loop or other connecting facility which shall be complementary to the connecting means of the frame and which is subject matter of the instant invention. Each cord 40 attaches to a hooked member 19 and is locked against unintended release by a spring member 20 which also prevents turning of the hooked member.

To illustrate in greater detail, and referring to Fig. 2, a hooked connector 19 comprising the hooked end 21 and threaded shank 22 is screwed into the wood or other material of the rail 10. The shank 22 is as long as required for holding and also provides for a small amount of adjustment in levelling the frame. Of course, there are other ways to adjust the position and limits of movement of the mechanism, and this adjustment serves as a final means of effecting a slight alteration in the relationship of the parts, 55 and incidentally, a simple and very speedy one.

The hooked part of the connector is desirably to be maintained directed as shown in order to avoid interference. It is also desired that once set, the position of a hook will not become changed during normal operation. The spring lock 20 is attached by screw 23 to the rail 10 and is so formed that normally it maintains the position it occupies in Fig. 2. The free end of the locking member is slotted as at 24, this slot being a free fit over the hooked end 21. The slot might be open ended, but that is not preferred. When a hook, ring or other complementary connector at the end of cord 18 is to be attached, the member 20 is pressed toward the rail 10 until the open end of the hook is exposed for the reception of the ring or the like. When the parts are linked together the lock is released and it immediately snaps back to hook closing position.

Similarly, if an adjustment is to be made the lock is pressed toward the rail until the slot is freed from the hooked end. One or more turns of the hook in either direction may be made as required whereupon the lock may be released and will automatically spring back to its normal position.

A whole or a half turn may be made, the length of slot 24 being sufficient to accommodate the hook when headed in either direction.

Now referring to Fig. 3, similar parts are indicated by like numerals with primes. The spring locking member here is of different shape and is considerably stiffer if of the same gauge material. It has two slots 25 and 26 so it may not be sprung out beyond the hook loop. It is adapted to function with an open hooked member only and when adjustments are made they are limited to a full turn of the hook.

In Fig. 4, the hooked member 27 is closed or in form of an eye screw and thus must function with some complementary member adapted to be hooked into it. The function of the locking member is the same, pressure of the free end of the spring against a hook or the like which constitutes the connecting means at the cord end retains it against accidental displacement.

The term "hooked member" includes either an open or closed connector such as that at 19 or 21, and the terms "slotted strip," "locking means," etc., refer to the parts 20, 20' or fair equivalents thereof as covered by the appended claims.

It is to be understood that attaching means subject matter of the case may be used at all points of connection of the harness to the frame, or at some only of those points.

While eye screws or hooks such as these are well adapted to be threaded into wood, they may be of the type to thread into metal rails or into metal or other inserts or the like held in the material of the rail in any convenient manner.

Normally but not necessarily, adjustment of a hook involves disconnecting a cord therefrom.

While certain preferred embodiments of the invention have been disclosed, it is to be understood that the invention is not limited thereto.

This patent is, therefore, not to be limited other

than is necessary by the scope of the appended claims.

I claim:

1. For loom harness frames which have top and bottom rails to which are connected harness cords, an improved harness cord attaching means which comprises a hooked member threadedly connected to a rail of the frame and adapted to receive a complementary attaching portion of a harness cord, and means to prevent unintended detachment of the cord and for maintaining the hooked member in a predetermined, adjusted position which comprises a spring means one end of which is attached to the rail of the frame, means at the opposite end of said spring means defining a slot of sufficient length to embrace the hooked portion of said hooked member when the latter is aligned therewith, the resilience of said spring means being such as normally to maintain its slotted end in engagement with the hooked end of the hooked member.
2. For loom harness frames which have top and bottom rails to which are connected harness cords, an improved harness cord attaching means which comprises a hooked member having a threaded shank for engagement in a rail of the frame and adapted to receive a complementary attaching portion of a harness cord, and a means to prevent unintended detachment of the cord and for maintaining the hooked member in a predetermined, adjusted position, said means comprising a resilient strip attached at one end to the frame at a point adjacent the said hooked member, the opposite end of said strip defining a slot of length and width sufficient to embrace the hooked portion of the member and to prevent rotation thereof as long as the slotted strip is in engagement therewith, said opposite end being relatively free and normally maintained by the resilience of the strip in position to engage the hooked portion of the hooked member.
3. Mechanism as defined in claim 2 wherein said hooked member is open for the reception of the complementary attaching means.
4. Mechanism as defined in claim 2 wherein said hooked member is formed as a substantially closed eye.
5. Mechanism as defined in claim 2 wherein said resilient strip is provided with a slot divided intermediate its ends so one part thereof embraces the hook shank while the other embraces the hook end.
